UNITED STATES PATENT OFFICE.

ALBERT D. GROVER, OF MALDEN, MASSACHUSETTS, ASSIGNOR, BY MESNE ASSIGNMENTS, TO AUTOSALES CORPORATION, A CORPORATION OF NEW YORK.

COIN-TESTER FOR COIN-CONTROLLED VENDING-MACHINES.

1,373,422.

Specification of Letters Patent.

Patented Apr. 5, 1921.

Application filed July 25, 1913. Serial No. 781,072.

To all whom it may concern:

Be it known that I, ALBERT D. GROVER, a citizen of the United States, and a resident of Malden, in the county of Middlesex and 5 State of Massachusetts, have invented new and Improved Coin-Testers for Coin-Controlled Vending-Machines, of which the following is a specification.

The object of my present invention is to 10 provide a coin-tester of such compact form that it may be applied to vending machines of small dimensions, such as machines used in theaters—without materially increasing the size of the machine. The coin-tester of 15 my invention is adapted to prevent the insertion of washers as well as checks of soft material into the coin-slot of the machine.

One of the chief drawbacks of vending machines of small proportions is that they 20 have not been provided with a coin-testing device, particularly a device for preventing the insertion of washers which are perhaps the most common means employed by unscrupulous persons for defrauding vending 25 machines. The coin-testing devices of the prior art are not, as far as I know, applicable to small machines, because those devices occupy so much space as to render their application to small machines entirely out of 30 the question. On the other hand, my new coin-tester occupies such exceedingly small space that it may be completely housed within the top plate of a theater machine, which may not be more than four inches wide and 35 one and one-half inches deep. The thickness of the plate housing my new coin-tester need not be more than one fourth of an inch. The proportions of the housing plate could even be smaller than those mentioned, 40 so exceedingly simple is the mechanism of my new and improved coin-tester. Considered in its broad aspect, my invention comprises mechanism associated with the coin-slot of a vending machine and adapted to 45 be automatically operated by an entering washer to lock the latter against full entrance into the slot. While the mechanism stops the washer against inward movement, it readily permits the same to be withdrawn 50 by hand so that the coin-slot may be cleared. The mechanism offers no obstruction to the passage of a good coin through the slot.

More specifically considered, my new coin-tester comprises a movable locking member 55 arranged to be projected across the coin-slot

into the opening of a partially inserted washer, whereby the latter is locked against full entrance into the slot, and means actuated by the entering washer for controlling or permitting operation of the movable 60 member into locking position. In the particular embodiment illustrated, this actuating means for the locking member consists of a pivoted lever having one portion extending across one end of the coin-slot to 65 be engaged by the entering washer, and a second portion arranged to engage the locking member and cause operation thereof when the washer engages the lever.

In the preferred form of my invention, 70 as illustrated in the accompanying drawings, the actuating lever cooperates with a second lever arranged at the other end of the slot to prevent the insertion of soft checks into the machine. These two levers 75 have sharp edges so arranged as to bite into a check of soft or yieldable material, and thereby prevent the same from passing through the slot. The accompanying drawings illustrate my invention in the form now 80 best known to me, although it is obvious that the broad principle of my invention may be mechanically carried out in other ways than that shown. In these drawings—

Figure 1, represents the top plate of a 85 coin-controlled vending machine in which my new coin-tester is housed.

Fig. 2, is a view similar to Fig. 1, with the cover removed to expose the parts of my new coin-tester, these parts being shown in normal or unoperated position.

Fig. 3, is a view similar to Fig. 2, with the parts in operated position.

Fig. 4, represents a section on the broken line 4—4 of Fig. 3.

Fig. 5, is a transverse cross-section on line 5—5 of Fig. 1, showing how a check of soft material is held against insertion through the coin-slot.

Fig. 6, is a view similar to Fig. 5, showing how a good coin is allowed to pass through the coin-slot, this figure being a cross-section on line 6—6 of Fig. 3.

Fig. 7, is a view similar to Fig. 5, showing a washer in locked position; and

Fig. 8, is a view similar to Fig. 4, on line 8—8 of Fig. 7.

The base plate 1 may form any suitable portion of the outside casing of a coin controlled machine. In the particular instance 110

illustrated, the plate 1 is supposed to form the top plate of a suitable vending machine. Inasmuch as my invention is applicable to almost any form of coin-controlled machine, 5 and is entirely independent in its construction and operation of any particular form of machine, I have not deemed it necessary to illustrate any specific form of vending or other machine in the drawings. It is sufficient to say that the base plate 1 is adapted to be secured to a suitable vending or other machine in any desired manner, as by means of screws or rivets. The plate 1 is formed with a coin-slot 2, and with recesses 3 and 4. 10 These recesses are so shaped as to properly accommodate certain parts therein. In the recess 3 is pivoted the lever 5 upon the stud 6. The end 7 of this lever normally projects across one end of the coin-slot 2, as best shown in Fig. 2, while the other end 8 of the lever is normally in engagement with the shoulder 9 of the locking bolt 10, which is slidably mounted in the recess 3. A spring 11 bears at one end against the outer end 7 of the lever 5 and normally holds the same in the position shown in Fig. 2. The spring 11 is mounted on the stud 12 in the recess 3. In the extended portion 3a of the recess 3 is housed the compression spring 13 which 20 bears against the rear end of the locking member or bolt 10. The free or outer end of the bolt 10 is tapered on its underside, as shown at 14 in Figs. 4 and 8. When the bolt is operated into locking position, the 25 tapered end 14 is projected across the coin-slot. The extreme tip of the tapered end rests in the small recess 15 formed in the plate 1 in alignment with the portion 16 of the recess 3. When the spring 13 is free to 30 act, it projects the bolt 10 into the locking position shown in Figs. 3 and 4. This action of the spring 13 is normally prevented by the stronger spring 11, which normally holds the inner end 8 of the lever 5 in engagement 35 with the shoulder 9 of the bolt 10.

In the recess 4 of the plate 1 is arranged the lever 17 which is pivotally mounted on the stud 18. A suitable spring 19 held on the stud 20 bears at one end against the 40 shoulder 21 of the lever 17 to normally hold the testing end 22 of this lever across the adjacent end of the coin-slot 2. This is best shown in Fig. 2. The outer or testing ends of the levers 5 and 17 are beveled so as to 45 provide cutting edges 23 and 24, respectively, as best shown in Figs. 5, 6 and 7.

The operation of my coin-testing device will be clearly understood from the foregoing description and is as follows:

When the proper coin—as for instance a nickel—is inserted into the slot 2, the hard edge of the coin bears against the edges 23 and 24 of the levers 5 and 17, and wedges them apart, thereby clearing the slot for the 65 entrance of the coin, which drops into the

machine and thereby performs the desired function, which may be either to release the delivery-mechanism for operation or to connect the delivery-mechanism with the hand-operated member on the outside of the machine, or control any suitable mechanism within the machine. In Figs. 3 and 6, the coin C is shown as having forced the levers 5 and 17 apart and passing through the coin-slot. The actuation of the lever 5 by the entering coin has no effect upon the bolt 10, because the free end of the bolt simply bears against the entering coin by slight frictional contact, without interfering with its passage through the coin-slot. The spring 13 is only a very light spring and does not project the bolt 10 against the entering coin with any appreciable force. It will be clear from a consideration of Fig. 6, 70 that when the coin has been inserted more than half-way the spring-pressed end 7 of the lever 5 (and the spring-pressed end 22 of the lever 17, whenever the latter is used) 75 will snap the coin through the coin-entrance slot. In this way the washer-catching mechanism of my invention not only forms no obstruction to the passage of a good coin but actually assists or accelerates the passage of a proper coin through the coin-entrance slot. 80

Should a check of soft material, such as 85 lead, paper or the like, be inserted into the coin-slot, the cutting edges 23 and 24 of the levers 5 and 17 will bite into the material and be prevented from separating, whereby 90 the check is locked against entry into the coin-slot. This is clearly shown in Fig. 5, 95 where the coin-testing edges 23 and 24 are shown as having entered the soft material 100 of the check L.

Let us now suppose that a washer of hard 105 material is inserted into the coin-slot 2. The first effect of the entering washer will be to force the free ends of the levers 5 and 17 apart, the same as an ordinary coin would. The washer will therefore enter the coin-slot 110 until the opening 25 of the washer (see Figs. 7 and 8, where the washer is indicated by W) comes into alignment with the locking bolt 10, whereupon the spring 13 thrusts the bolt through the washer opening and thereby locks the washer against further entry 115 into the coin-slot. The entering washer moves the lever 5 from the position shown in Fig. 2 to that shown in Fig. 3, thereby releasing the bolt for operation under the influence of the spring 13. However, this operation of the bolt 10 does not take place 120 until the opening 25 of the washer comes into alignment with the bolt. While the washer is thus locked against full entry into 125 the coin-slot, the beveled underside 14 of the bolt 10 permits the washer to be readily withdrawn by hand, so that the coin-slot may be cleared. This is an important function of my new coin-testing device, for 130

otherwise the machine would be rendered useless by the first insertion of a washer. As the washer is withdrawn, the strong spring 11 forces the lever 5 back into normal position against the action of the weak spring 13. The movement of the lever 5 to normal position also moves the locking bolt 10 back into normal position. In the broad aspect of my invention, the controlling connection 10 between the operating lever 5 and the locking bolt 10, might be carried out in other ways than that shown. However, I prefer to employ the arrangement shown in the drawings, in which the lever 5 normally restrains the spring 13 from projecting the bolt into locking position.

The parts of the coin-testing mechanism are covered by the plate 26 which is secured over the plate 1 in any desired manner, as 20 by screws or rivets 27.

It will be seen from the foregoing that I have provided an exceedingly simple and at the same time highly effective coin-testing device for positively preventing the insertion 25 into the coin-entrance slot of washers and of checks made of soft or yieldable material. The exceedingly small space that the parts occupy renders my invention applicable to small machines which had hitherto 30 been unprotected against fraudulent operation by washers or disks of soft material. While this invention was primarily intended for coin-controlled vending machines, it is obvious that it may be applied to coin-controlled 35 machines of any kind.

Having thus described my invention what I claim as new and desire to secure by Letters Patent of the United States is:

1. In a coin-controlled machine having a 40 coin-slot for receiving a coin edgewise, washer-catching mechanism having a yieldable part adapted to engage in the opening of a partially inserted washer to lock the same against full entrance into the slot, and 45 a second yieldable part extending across one end of said coin-slot to be thereby actuated by the entering washer and control the operation of said locking part, said mechanism permitting ready removal of the locked 50 washer to clear the coin-slot, said second yieldable part engaging an entering good coin on the edge thereof and thereby snapping it through said slot.

2. In a coin-controlled machine having a 55 coin-slot for receiving a coin edgewise, the combination of a spring-pressed locking member arranged to be projected across said coin-slot into the opening of a partially inserted washer, whereby the latter is locked 60 against full entrance into said slot, said member permitting the withdrawal of the intercepted washer, and means mounted independently of said member and adapted to be actuated by the entering washer to control the operation of said member,

3. In a coin-controlled machine having a coin-slot, the combination of a spring-pressed locking member arranged to be projected across said coin-slot into the opening of a partially inserted washer, whereby the latter is locked against full entrance into the coin-slot, said member permitting the withdrawal of the intercepted washer, and a pivoted lever mounted independently of said locking member for controlling the operation thereof, said lever having a portion extending across one end of the coin-slot to be engaged by the entering washer, whereby said lever is actuated by the entering washer to control the operation of said locking member into locking position.

4. In a coin-controlled machine, a flat plate provided with a coin-slot for receiving a coin edgewise, said plate being provided with a recess or chamber, a spring-pressed locking member mounted in said recess or chamber and adapted to be projected across said coin-slot into the opening of a partially inserted washer, whereby the latter is locked against full entrance into the slot, said member permitting withdrawal of the intercepted washer, and means mounted in said recess or chamber independently of said member and adapted to be actuated by the entering washer to control the operation of said locking member.

5. In a coin-controlled machine, a flat plate provided with a coin-slot for receiving a coin edgewise, said plate being provided with a recess or chamber, a spring-pressed locking member mounted within said recess or chamber and arranged to be projected across said coin-slot into the opening of a partially inserted washer, whereby the latter is locked against full entrance into the slot, 105 said member permitting the withdrawal of the intercepted washer, and a pivoted lever mounted in said recess or chamber for controlling the operation of said locking member, said lever having a portion extending across one end of said slot to be engaged by the entering washer, whereby said lever is actuated by the entering washer to control the operation of said locking member into locking position.

6. In a coin-controlled machine having a coin-slot, mechanism associated with said slot and adapted to be automatically actuated by an entering washer to lock the same against full entrance into the slot, said mechanism including a spring-pressed locking member arranged to be projected across the coin-slot into the opening of a partially inserted washer, said member permitting removal of the locked washer through said coin-slot, and a pivoted member mounted independently of said locking member and arranged to be actuated by the entering washer for controlling the operation of said locking member.

7. In a coin-controlled machine, a flat plate provided with a coin-slot for receiving a coin edgewise, mechanism carried by said plate for automatically locking an entering washer against full entrance into said slot, said mechanism including a spring-pressed locking member arranged to be projected across said coin-slot into the opening of a partially inserted washer, said member permitting removal of the locked washer through said coin-slot, and a controlling member mounted independently of said locking member and arranged to be actuated by the entering washer to control the operation of said locking member into locking position.

8. In a coin-controlled machine provided with a coin-slot, means adapted to engage in the opening of an entering washer and thereby lock the same against full entrance into said slot, and means adapted to be actuated by the entering washer for controlling the operation of said locking means, said locking means being mounted independently of said controlling means and permitting removal 25 of the locked washer through said coin-slot.

9. In a coin-controlled machine, a plate provided with a coin-slot for receiving a coin edgewise, a device carried by said plate for engaging in the opening of an entering washer and thereby locking the same against full entrance into said slot, said device permitting removal of the locked washer through said coin-slot, and a member also carried by said plate and adapted to be actuated by the entering washer for controlling the operation of said device, said device and said member being constructed and arranged to operate in a plane parallel to the plane of said plate.

40 10. In a coin-controlled machine provided with a coin-slot, the combination of a spring-pressed locking member normally adapted to be projected across said coin-slot to engage in the opening of an entering washer and thereby lock the same against full entrance into the slot, said member permitting removal of the locked washer through said coin-slot, and a spring-pressed member normally holding said locking member in an 45 operative position, said second member being adapted to be actuated by an entering washer to release said locking member for operation into locking position.

11. In a coin-controlled machine, a flat plate provided with a coin-slot and with a recess or chamber, a movable locking member mounted within said recess and provided with a light spring which normally tends to project said member across the coin-slot, a lever mounted within said recess for controlling the operation of said locking member, and a heavy spring which normally holds one portion of said lever across one end of the coin-slot and the other portion 65 against said locking member to hold the

same against operation by said light spring, said controlling lever being adapted to be actuated by an entering washer to release said locking member for operation into locking position, said locking member being adapted to enter the opening in the washer and thereby lock the same against full entrance into the slot.

12. In a coin-controlled machine provided with a coin-slot, the combination of a slide- 75 able spring-pressed locking member normally adapted to be projected across said coin-slot to engage in the opening of an entering washer and thereby lock the same against full entrance into the slot, and a pivoted spring-pressed member normally holding said locking member in an inoperative position and adapted to be rocked by an entering washer to release said locking member for operation into locking position, said locking member permitting removal of the locked washer through said coin-slot.

13. In a coin-controlled machine provided with a slot for receiving a coin edgewise, a spring-pressed locking member normally 90 adapted to be projected across said coin-slot to lock an entering washer against full entrance into the slot, said locking member permitting removal of the locked washer through said slot, and a spring-pressed member normally holding said locking member in an inoperative position and adapted to be actuated by the entering washer to permit operation of said locking member into locking position, said members being mounted 95 independently of each other.

14. In a coin-controlled mechanism provided with a coin-slot, a movable locking member adapted to be projected across said coin-slot to lock an entering washer against 105 full entrance into the slot, a spring for actuating said member into locking position, a movable device for controlling the operation of said locking member, a spring connected with said device for normally holding the same in position to maintain said locking member in withdrawn or inoperative position, said last-mentioned spring being stronger than said first spring, and means whereby an entering washer actuates said controlling device into such a position that said first-mentioned spring causes operation of said locking member into locking position.

15. In coin-controlled mechanism provided with a coin-slot, a movable locking member adapted to be projected across said coin-slot to lock an entering washer against full entrance into the slot, a spring for actuating said member into locking position, a movable device for controlling the operation of said locking member and having a portion extending across one end of the coin-slot to be engaged by an entering washer, and a spring connected with said device for normally holding the same in a position to maintain 120 125 130

5 said locking member in withdrawn or inoperative position, said last-mentioned spring being stronger than said first spring, whereby the entering washer actuates said controlling device into such a position that said first-mentioned spring causes operation of said locking member into locking position.

10 16. In coin-controlled mechanism provided with a coin-slot, a movable locking member adapted to be projected across said coin-slot to lock an entering washer against full entrance into the slot, a spring for actuating said member into locking position, a pivoted lever for controlling the operation of said locking member, a spring connected with said lever for normally holding the same in a position to maintain said locking member in withdrawn or inoperative position, said last-mentioned spring being stronger than 15 said first spring, and means whereby an entering washer actuates said controlling lever into such a position that said first-mentioned spring causes operation of said locking member into locking position.

20 25 17. In coin-controlled mechanism provided

with a coin-slot, a movable locking member adapted to be projected across said coin-slot to lock an entering washer against full entrance into the slot, a spring for actuating said member into locking position, a pivoted 30 lever for controlling the operation of said locking member and having a portion extending across one end of the coin-slot to be engaged by an entering washer, and a spring connected with said lever for normally holding the same in a position to maintain said locking member in withdrawn or inoperative position, said last-mentioned spring being stronger than said first spring, whereby an entering washer actuates said controlling 35 lever into such a position that said first-mentioned spring causes operation of said locking member into locking position.

In witness whereof, I hereunto subscribe my name this 14th day of July 1913.

ALBERT D. GROVER.
